By David O. Barnett,

Attorney.

UNITED STATES PATENT OFFICE.

FRED E. HALE, OF OMAHA, NEBRASKA, ASSIGNOR, BY MESNE ASSIGNMENTS, TO UNITED STATES CARBURETOR COMPANY, A CORPORATION OF NEBRASKA.

CARBURETER ACCESSORY.

1,273,363.

Specification of Letters Patent. Patented July 23, 1918.

Application filed June 1, 1916. Serial No. 101,177.

To all whom it may concern:

Be it known that I, FRED E. HALE, a citizen of the United States, and a resident of Omaha, in the county of Douglas and State 5 of Nebraska, have invented certain new and useful Improvements in Carbureter Accessories, of which the following is a specification.

My invention relates to charge-forming 10 devices for internal combustion engines, and particularly to auxiliary means adapted for use in connection with carburetors, for pre-heating both the fuel and air supplied to the carburetor, and for supplying and vaporizing water to be mixed with the air for humidifying the same before it enters the carburetor proper. It is the object of my 15 invention to provide a simple and efficient device for performing each of the above mentioned functions, the device being constructed and adapted for connection with the exhaust pipe of the engine, so that the necessary heat is supplied by the exhaust 20 gases or combustion products from the engine.

In the accompanying drawings Figure 1 is a partially diagrammatic side view of a device embodying my invention, together with the various mechanism connected and 25 associated with the same when in use, Fig. 2 is a detail side elevation of the heating device, Fig. 3 is a transverse section of the same on the plane of the line 3—3 of Fig. 2, Fig. 4 is a longitudinal vertical section of 30 the same, and Fig 5 is a transverse section on the irregular or broken plane of the line 5—5 of Fig 4.

The illustrated embodiment of my invention is especially adapted for use on a motor- 40 vehicle driven by an internal combustion engine having a two-fuel carburetor of the general type shown in the patent application of Woolf and Hale, filed Feb. 13, 1915, Serial No. 8046. In Fig. 1 there is indicated 45 a carburetor 6, of the kind referred to, together with various accessories and connections thereof. Thus, there are shown supply-tanks 7 and 8 for the two fuels, the first being used to contain kerosene or dis- 50 tillate, and the second for a lighter and

more volatile fuel such as gasolene. From the tank 8 a connecting supply-pipe 9 is extended directly to and suitably connected with the carburetor. There are also shown a part of the intake pipe 10 which extends 55 from the carburetor to the engine, a part of the exhaust-pipe 11 of the engine, the muffler 12 with which the exhaust-pipe is connected, the radiator 13 used in the water-cooling system for the engine, a water circulating 60 pump 14, and a part of the dash or foot-board 15 of the vehicle. All of the foregoing parts are indicated in the drawing merely for the purpose of showing their relation to the devices embodying my invention, and are not comprised within the latter.

The principal device provided by my invention is the fuel and air heater and air-moistener or humidifier, of which the detailed construction is shown in Figs. 2 to 70 5, inclusive. Said heating device comprises a jacketed flue through which the exhaust gases from the engine are passed, the flue being in two portions 16 and 17 secured 75 together longitudinally, and having the ends thereof connected by means of the caps 18 with the portions of the exhaust-pipe 11 through which the heated gases are supplied thereto and discharged therefrom. The central passage through the jacketed flue portions 16 and 17 is ribbed or quatrefoliate in section, the outer parts or jackets being cylindrical, and the jackets and central flue parts being connected with each other by 80 integral end-portions. The caps 18 are approximately semi-spherical in form, the diameter thereof being the same as that of the jackets of the flue portions against which they are fitted. At the edges of the caps 85 19 are perforate lugs 19, and similar lugs 20, having threaded openings therein, are provided at the ends of the long flue section 16. The short flue-section 17 has a single set of 90 perforate lugs 21 disposed intermediate of its ends. Screws 22 extend through the lugs 19 of one cap, entering the threaded openings of the lugs 20 at the adjacent end of the flue-section 16 to secure the cap upon 95 said flue-section. At the other end, long 100

screws 23 pass through the lugs 19 of the cap, thence through the lugs 21 of the short flue-section 17, and then enter the threaded openings of the lugs 20 at the adjacent end 5 of the section 16. The short flue-section is thus secured between the cap and the end of the long flue-section. At the central part of each cap 18 is a clamp-nipple 24 having a slot or kerf at one side, and provided with a screw 25 which may be tightened 10 to close the kerf and clamp the nipple onto the exhaust-pipe 11.

On the lower side of the jacket of the flue-section 16, near one end thereof, is a 15 nipple or tubular boss 26, and near the opposite end of said flue-section on the upper side thereof is a similar nipple 27 with which is connected a tubular elbow 28. From the latter a flexible pipe 29 is extended 20 to the air-inlet of the carbureter 6, so that the air which enters the carbureter must be drawn through the heater, entering the jacket of the section 16 at the nipple 26, thence circulating through the space 25 within the jacket, and then passing through the elbow 28 and pipe 29 to the carbureter.

A certain quantity of water is supplied to the heater, so as to be vaporized therein and mixed with the heated air passing to the 30 carbureter, as follows: From the discharge-pipe of the water-circulating pump 14, a small pipe 30 is extended to a sight-feed valve 31 arranged on the dash or foot-board 15 of the vehicle, as shown. From said 35 valve 31 another small pipe 32 is extended to the heater and connected with a nipple 33 which is arranged adjacent to the nipple 27 on the jacketed-section 16. The flow of water from the pump through the tubes 30 40 and 32 is regulated by the valve 31, and the water enters the jacket of the heater so as to fall onto the heated inner flue-portion thereof, where it is vaporized and mingles with the air so as to moisten and humidify the 45 same.

The short jacketed flue-section 17 is used for heating the fuel from the supply-tank 7 before said fuel passes to the carbureter. From said tank 7 a small feed-pipe 34 is 50 extended to and connected with a nipple 35 at one side of the jacket of said flue-section 17, so that the fuel is supplied through said pipe to the space within the jacket, as shown in Fig. 3. A pipe 36 is connected 55 with another nipple 37 on the side of said jacket, and extends therefrom to an opening in the elbow 28, passing into the elbow as shown in Fig. 2, and thence through the pipe 29 to the carbureter. The fuel, becoming 60 heated while within the jacket-chamber of the section 17, passes through the pipe 36 to the carbureter, and, as the greater portion of said pipe 36 is inclosed by the pipe 29

and thus surrounded by the heated air, the fuel is maintained in a heated condition.

65

When installing the heating device, besides supplying the required connecting piping therefor, it is merely necessary to remove a section of the exhaust-pipe 11, and to substitute the heater for the removed portion of the exhaust-pipe by clamping the caps 18 onto the ends of the remaining portions of the pipe. From the foregoing it will be apparent that my invention provides a simple and effective heating and humidifying device which, in connection with a suitable carbureter, may be readily attached to any motor-vehicle now in common use, where such vehicle employs an internal-combustion engine for its motive power.

70

75

80

Now, having described my invention, what I claim and desire to secure by Letters Patent is:

1. A fuel and air heating and humidifying device for carbureters, comprising a plurality of jacketed flue-sections having central longitudinal passages, means for connecting the same serially in the exhaust-line of an engine, means for directing air to a carbureter from the jacket-space of one of the flue-sections, means for supplying water to said jacket-space, means for supplying liquid fuel to the jacket-space of another flue-section, and means for directing the fuel from said jacket-space to the carbureter, said fuel-directing means being arranged to be heated by the air from the first-named jacket-space.

85

2. In a device of the class described, a plurality of integral jacketed flue-sections having longitudinal passages and jacket-spaces surrounding the same, means for connecting said flue-sections serially in the exhaust-line of an engine, means for directing air and liquid fuel into the respective jacket-spaces, and means for directing the air and fuel from said jacket-spaces to a carbureter.

90

3. In a device of the class described, a longitudinally-ribbed flue having an inclosing jacket spaced therefrom and connected therewith by integral imperforate end-portions extending transversely to the axis thereof, caps adapted to fit upon the ends of said flue and detachably connected therewith, clamping means on said caps for detachably retaining the same upon the ends of a pipe, and means forming air inlet and outlet passages from the space within the jacket.

105

4. In a device of the class described, a flue-section having a longitudinal ribbed passage through it, a jacket inclosing said flue-section and forming a chamber around the same, means for admitting and discharging air from said chamber, a second

110

115

120

125

flue-section having a jacket and inclosed chamber similar to the first, means for admitting and discharging a liquid fuel from the chamber of said second flue-section, and 5 caps removably connected with the ends of the first flue-section, the second flue-section being clamped between the end of the first

and one of said caps, and said caps being detachably connected with means for admitting and discharging a heating medium 10 from the longitudinal passage through the flue-sections.

FRED E. HALE.
